ABSTRACT: Magazines are delivered to a hopper and are successively fed from the hopper onto a conveyor by an oscillating shuttle and a pair of driven pinch rolls. The shuttle is operated in timed relation with the conveyor through a clutch controlled by a pneumatic valve including a pistonlike valve member. A paddle senses the stack height of the magazine within the hopper and actuates the valve member. Air is continuously exhausted from the valve, and the flow rate of the exhausting air is adjustable to vary the stack height of the magazines within the hopper.

CONTROL APPARATUS FOR BOOK HOPPER

BACKGROUND OF THE INVENTION

In the binding and trimming of books or magazines, it is common to collect a stack of the magazines within a hopper as the magazines are fed from binding machinery towards a trimmer. The magazines are successively fed by a conveyor from the bottom of the hopper to the trimmer where each magazine is trimmed to a predetermined size. Sometimes, the magazines are fed from the hopper onto the conveyor by an oscillating shuttle which is operated in timed relation to the conveyor by an oscillating shuttle which is operated in timed relation to the conveyor and in response to the stack height of the magazines collected within the hopper. One system which has been employed to operate the shuttle incorporates limit switches which sense the upper and lower levels of the stack of magazines within the hopper and control solenoid valves in the air supply lines to an air cylinder which actuates a clutch in the drive mechanism for the shuttle. It has been found that this system does not provide dependable service and does not enable the upper limit or height of the stack of magazines within the hopper to be conveniently set or changed according to the size of magazines being handled.

SUMMARY OF THE INVENTION

The present invention is directed to an improved apparatus for controlling the height of a stack of magazines, books or similar articles collected within a hopper. The apparatus is convenient to install and provides for quickly selecting the upper limit or maximum height of the stack of magazines collected within the hopper. Furthermore, the apparatus of the invention is simple in construction and dependable in operation, and provides a positive control of the shuttle which successively feeds the magazines from the bottom of the hopper. For purposes of this application, the term "book" is used to include magazines, booklets and the like.

In accordance with a preferred embodiment of the invention, the control apparatus includes a sensing paddle which is supported for swinging movement adjacent the hopper and which has a projection extending into the hopper. The lower swinging end of the paddle engages a plunger extending from a pistonlike valve member supported for axial movement within a cylindrical chamber of a pneumatic control valve. Pressurized air is supplied to the valve chamber, and a small flow of air is continuously exhausted from the chamber through a passage controlled by a needle valve.

The piston has axially spaced circumferential grooves which cooperate with airports or passages connected to an air cylinder which operates a clutch within the drive mechanism connecting the feed conveyor to the oscillating shuttle. Predetermined movement of the sensing paddle in response to buildup of magazines within the hopper is effective to move the valve piston thereby controlling the operation of the air cylinder and the shuttle feed. Adjustment of the needle valve within the exhaust passage is effective to control the back pressure on the pistonlike valve member thereby varying the force required to be exerted on the valve member by the sensing paddle to select the stack height of books required within the hopper to operate the shuttle feed.

BRIEF DESCRIPTION OF THE DRAWING

FIG. 1 is a somewhat diagrammatic view in part section of a book hopper and control apparatus constructed in accordance with the invention;

FIG. 2 is a section taken generally on the line 2-2 of FIG. 1; and

FIG. 3 is a schematic diagram of the control apparatus with the pneumatic control valve shown in axial section.

DESCRIPTION OF THE PREFERRED EMBODIMENT

Referring to FIG. 1, an endless conveyor 10 is directed around a set of end rollers 11 of which is driven by a motor 12. The conveyor 10 extends from a bookbinder (not shown) and successively conveys a series of books B on a random basis from the binder to a hopper 15 having a rectangular cross-sectional configuration formed by opposite sidewalls 16 and 17 (FIG. 2) connected by an end wall 18 (FIG. 1) and a bottom wall 19. A vertical guide shoe 20 is positioned in opposing relation to the end wall 18 and is located adjacent the wall 16. A platelike shuttle 21 is slidably supported by the bottom wall 19 and is connected by a pivot pin 22 to an arm 23 pivotally supported by a pin 24.

15 An endless conveyor 25 (FIG. 2) is directed around a set of end rolls 26 and has an upper run which extends below the bottom wall 19 of the hopper 15. The conveyor 25 includes longitudinally spaced sets of lugs 28 which are adapted to engage the books B as they are successively fed from the bottom of the hopper 15 by the cooperation of the shuttle 21 and a set of driven pinch rolls 30. Each book B is delivered to the book trimmer (not shown) which shears the edges of the book according to predetermined dimensions. The conveyor 25 is driven by the trimmer drive 32 connected to one of the end rollers 26, and the shuttle arm 23 is oscillated in timed relation with the trimmer drive 32 by actuation of a clutch 33 which operates a cam mechanism (not shown) connected to the arm 23. A double-acting air cylinder 34 is connected to control the clutch 33.

In accordance with the invention, a sensing member or paddle 35 extends vertically adjacent the hopper wall 17 in opposed relation to the wall 18 and cooperates with the guide shoe 20 to confine a stack of books B within the hopper. The upper end portion of the paddle 35 is pivotally supported by a shaft or pin 37 secured to a vertical frame 38. A cam member 40 is secured to the paddle 35 by a screw 41 which extends through a vertical slot 42 formed within the paddle 35. The cam member 40 has a curved or contoured surface 44 facing inwardly of the hopper 15 and which is adapted to be engaged by the leading edges of the book B as will be explained later.

The frame 38 includes a horizontally projecting bracket 48 which supports a pneumatic control valve 50 including an elongated blocklike housing 52. A cylindrical chamber 55 extends longitudinally within the housing 52 and has an inner end connecting with an exhaust passage 56 which receives the inner end portion of an adjustable needle valve member 57. A cylindrical piston 60 is slidably mounted within the chamber 55, and a smaller diameter cylindrical plunger 62 projects from the piston 60 through a hole formed within a retainer plate 63. The outer end of the plunger 62 engages the lower end portion of the sensing member or paddle 35.

55 A pair of axially spaced circumferential grooves 65 is formed within the piston 60, and two sets of diametrically arranged ports 67 and 68 extend through the housing 52 to the chamber 55. The axial spacing between the grooves 65 is less than the longitudinal spacing between the ports 67 and 68 so that axial movement of the piston 60 within the housing 52 is effective to open alternately each set of ports 67 or 68 or to close both sets of ports.

60 Air supply lines 70 are connected to the ports 67 and 68 on one side of the chamber 55, and corresponding lines 72 connect the ports 67 and 68 on the opposite side of the chamber 55 to opposite ends of the air cylinder 34. The outer diameter of the piston 60 is slightly less than the inner diameter of the valve chamber 55 so that air supplied to the chamber 55 through the air lines 70 flows axially within the chamber 55 in the annular clearance surrounding the piston 60 and escapes through the exhaust port 56. This provides a low friction floating support for the piston 60.

65 In operation, books are successively delivered to the hopper 15 by the conveyor 10 and when the stack of books within the hopper build up to a level where the uppermost books engage 70 the cam member 40, an outward force is urged on the paddle

35 causing the lower end portion of the paddle to swing outwardly and depress the plunger 62 to urge the piston 60 inwardly within the valve chamber 55. When the innermost groove 65 within the piston 60 moves into general alignment with the port 67, the corresponding line 72 is pressurized thereby actuating the air cylinder 34 causing the clutch 33 to effect oscillation of the shuttle arm 23 for successively feeding the books B from the bottom of the hopper 15.

When the stack of books B within the hopper 15 reduces to a level below the projecting member 40 on the paddle 35, the lower end portion of the paddle 35 swings away from the control valve 50 causing the piston 60 to move to the right (FIG. 3) within the chamber 55 when the outermost groove 65 within the piston 60 becomes generally aligned with the port 68, the corresponding line 72 is pressurized causing the cylinder 34 to disengage the clutch 32 and stop the oscillation of the shuttle arm 23.

As a result of the continuous escape of air through the exhaust passage 56, the force exerted by the plunger 62 against the lower end portion of the paddle 35 can be conveniently controlled merely by adjusting the needle valve member 57. That is, when the air flowing through the exhaust passage 56 is further restricted by screwing the valve member 57 inwardly, the air pressure adjacent the inner end surface of the piston 60 increases and thereby increases the force required to be exerted by the books B on the paddle 35 to shift the piston 60 inwardly to a position for actuating the air cylinder 34. Thus adjustment of the needle valve member 57 is effective to raise or lower the upperlimit of the stack of books B within the hopper 15 to a selected level.

From the drawing and the above description, it is apparent that a control apparatus constructed in accordance with the invention provides desirable features and advantages. That is, the pneumatic control system is simple in construction and can be conveniently installed adjacent one side of a book hopper. Furthermore, the apparatus can be easily adjusted to control the upper level of the books within the hopper. The pneumatic control apparatus has also been found to be highly dependable in operation and requires no significant servicing when compared to the conventional electrical control systems used heretofore.

While the form of apparatus herein described constitutes a preferred embodiment of the invention, it is to be understood

that the invention is not limited to this precise form of apparatus, and that changes may be made therein without departing from the scope and spirit of the invention.

What we claim is:

- 5 1. Improved apparatus for successively feeding booklike articles from a hopper adapted to receive the articles in a stacked manner, said apparatus comprising a shuttle member positioned adjacent the bottom of the hopper for reciprocating movement, means for reciprocating said shuttle member and including a clutch, air-actuated means for operating said clutch, a sensing member positioned adjacent said hopper, means supporting said sensing member for movement in response to a predetermined stack height of articles within said hopper, an air control valve including a body defining a 15 valve chamber, a valve member disposed for movement within said chamber, means for moving said valve member in response to movement of said sensing member, means for directing an air supply to said valve chamber, and means connecting said valve body to said air-actuated means for said 20 clutch to effect operation of said shuttle member in response to a predetermined stack height of articles within said hopper.
2. Apparatus as defined in claim 1 wherein said control valve includes means defining a passage for continuously exhausting air from said chamber, and means for varying the 25 flow of air through said passage to control the back pressure on said valve member for changing the stack height of articles required within said hopper to effect actuation of said valve by said sensing member.
3. Apparatus as defined in claim 1 wherein said valve 30 member includes a portion projecting from said body and engaging said sensing member to provide said means for moving said valve member.
4. Apparatus as defined in claim 1 wherein said valve 35 chamber and said valve member are cylindrical, means defining axially spaced circumferential grooves within said valve member, said directing means comprise axially spaced passages extending from said valve chamber, and the spacing between said passages being different from the axial spacing between said grooves.
5. Apparatus as defined in claim 4 wherein said valve body defines an exhaust passage for said valve chamber, and adjustable valve means for varying the flow of air through said exhaust passage.
